UNITED STATES PATENT OFFICE.

ALVIN WELLHOUSE, OF ATLANTA, GEORGIA.

DESIGN FOR A PAPER BAG.

SPECIFICATION forming part of Design No. 28,240, dated February 1, 1898.

Application filed June 18, 1897. Serial No. 641,361. Term of patent 31 years.

To all whom it may concern:

Be it known that I, ALVIN WELLHOUSE, a citizen of the United States, residing at Atlanta, in the county of Fulton, State of Georgia, have invented and produced a new and useful and original Design for Paper Bags, of which the following is a specification.

This invention has reference to a design for paper bags, and is fully shown in the accompanying drawing, in which is represented a bag formed of paper provided with my design.

The leading feature of my design consists of clovers arranged in pairs with their stems crossing, one of said clovers being represented with three leaves and the other with four leaves.

Referring to the drawing, *a* represents a

paper bag having printed on the material thereof a plurality of groups of clovers comprising a three-leaved clover *b* and a four-leaved clover *c*, the stems *d* and *e*, respectively, thereof being crossed, this group of clover being repeated throughout the material of which the bag is formed as often as may be desired and of whatever size may be wished.

Having thus described my invention, what I claim is—

The design for a paper bag substantially as shown and described.

In testimony whereof I affix my signature in presence of two witnesses.

ALVIN WELLHOUSE.
